UNITED STATES PATENT OFFICE.

WILLIAM D. COOPER, OF WHITE BEAR, MINNESOTA, ASSIGNOR OF FORTY-NINE TWO-HUNDREDTHS TO HENRY WEILLER AND FORTY-NINE TWO-HUNDREDTHS TO ROBERT C. SWEET, BOTH OF ST. PAUL, MINNESOTA.

TELEGRAPH TRANSMITTING INSTRUMENT.

Application filed July 9, 1923. Serial No. 650,345.

This invention relates to improvements in telegraph transmitting instruments of the type having a series of keys adapted to be manipulated to send different combinations of impulses.

As is well known, code combinations of short and long impulses, or dots and dashes, are commonly employed in commercial telegraphy. The codes now in use include a series of dots numbering up to six and it is these combinations of short impulses which are extremely difficult to send rapidly and accurately with the common type of telegraph key. Operators are unable to send messages as fast as they can receive them because of human limitations upon the ability to rapidly vibrate a key. Further, the sending of dot signals renders the operation of a transmitting instrument extremely fatiguing. Mistakes in sending messages are also largely due to inaccuracies in sending combinations of short impulses. It is true that machines have heretofore been devised for sending a series of impulses upon a single manipulation of a key, but as far as applicant is aware, none of these attempts have been successful from a commercial standpoint because the machines are either too complicated and expensive and not adapted for use with present day methods or are defective in that the messages transmitted thereby are indistinct. The latter defect is brought about by a failure to provide proper means for firmly closing the circuit in a mechanically operated switch.

It is my object to obviate these defects by providing a simple and efficient instrument whereby any required combination of dots for the commonly used codes may be sent by a single manipulation of a key.

It is a further object of this invention to provide a telegraph transmitting instrument by which messages may be sent at a greatly increased rate of speed, with greater accuracy, and at the same time with less effort on the part of the operator.

Another object of my invention is to provide a transmitting instrument which is adapted for use with present day methods of commercial telegraphy.

A further object of my invention is to provide an automatic switch in a telegraph instrument of this kind, with a resilient con-

tact adapted to simulate the human touch on a transmitter key of common type.

My invention also includes novel features of construction which will be more fully pointed out in the following specification and claims.

In the accompanying drawings I have illustrated the best form of my device at present known to me. Referring to the drawings, Fig. 1 is a plan view of my improved telegraph instrument; Fig. 2 is a rear elevation of the same; Fig. 3 is a detail side elevation of the keys for sending dashes; Fig. 4 is a section taken on the line 4—4 of Fig. 1; Fig. 5 is a detail elevation of the automatic switch, partially in section; Fig. 6 is a central, vertical section through the motor; Fig. 7 is a detail perspective view of the pawl for stopping the mechanism, together with the supporting arms therefor; Fig. 8 is a section taken on the line 8—8 of Fig. 3, and Fig. 9 is a section taken on the line 9—9 of Fig. 3.

My device is supported in a frame consisting of a base plate 10 formed with pairs of standards 11 and 12. A series of keys 13 to 17, inclusive, are adapted to be manipulated to send dots, each key being arranged to control mechanism for sending a different number of short impulses. The several keys 13 to 17 inclusive are pivotally supported upon a transverse rod 18 secured at its ends in the standards 11, and a series of collars 19 are provided to maintain the several keys in proper spaced relation on the rod 18. Rigidly connected with the several keys and extending across the top of the instrument from the rod 18 is a series of bars 20 which are normally supported at their free ends upon shoulders 21 formed on small levers 22 (Fig. 4). The levers 22 are tiltably carried upon a transverse rod 23 in the frame and a lug 24 on each of said levers is adapted, when the lever is tilted, to support the bar 20 in raised position.

A shaft 25 carrying a series of pinions 26 extends between the standards 11, being journaled therein. Fast on the shaft 25 adjacent to one of the standards 11 is a ratchet 27 adapted to be engaged by a pawl 28. The latter pawl, as clearly shown in Figs. 1 and 7, is supported upon a pair of arms 29 which are pivoted upon the rod 18 at one end and

formed with a cross bar 30 near the opposite end, the bar 30 being arranged to normally rest upon the upper edges of the bars 20. A small coiled spring 31 is secured at its upper end to the bar 30 and at its lower end to a transverse rod 32. The spring 31 thus normally maintains the cross bar 30 and bars 20 in the full line position shown in Figure 4. Pivotally joined to the several keys 13 to 17, inclusive is a series of rack arms 33 carrying racks 34 on their ends adjacent to the pinions 26. Supports 35 for the arms 33 are tiltable upon a transverse rod 36 and arranged to be adjusted as to height by suitable set screws 37.

Fast on one end of the shaft 25 is a cam wheel 38 adapted to actuate a switch bar 39. The latter bar is pivoted in obliquely inclined position upon a pin 40 and maintained in contact with the periphery of the wheel 38 by a spring 41. A small contact plunger 42 is maintained in extended position by a compression spring 43 in the bar 39. Mounted opposite the end of the plunger 42 is a contact screw 44 supported upon an insulated conductor 45. When the wheel 38 rotates, the upper end of the bar 39 is vibrated to make and break the circuit between the plunger 42 and contact 44.

To rotate the shaft 25 when the keys 13 to 17, inclusive are manipulated, I provide a spring actuated motor 46, Figs. 1, 2 and 6. This motor consists of a drum 47 mounted to revolve in the standards 12 and having an axial shaft 48 connected by a large gear 49 and a pinion 50 with the shaft 25. Rigidly secured to the shaft 48 within the drum 47 is a ratchet wheel 51 which is adapted to be normally engaged by a pawl 52 on the drum 47. A large convolute spring 53 is fastened at its outer end to the drum 47 and at its inner end to an inwardly projecting hub 54 on one of the standards 12. To adapt the spring 53 to be wound by a crank 55, the drum 47 is provided with a threaded stud 56 extending through the outer standard 12. The stud 56 is adapted to receive the crank 55, which has a threaded bore. Thus, by manipulating the crank 55 the drum 47 may be rotated to wind the spring 53, the pawl 52 being arranged to run free on the ratchet wheel 51 during the winding. When the spring 53 has been wound, it will tend to rotate the shaft 48 by means of the pawl 52 which now engages the teeth of the ratchet wheel 51 on the shaft 48. The shaft 25 is thus normally maintained under such a torque as to tend to rotate it in the direction indicated by arrows in Figs. 4 and 5, rotation being normally prevented by the pawl 28 in engagement with the ratchet 27.

Keys 57 and 58 mounted on one end of the base plate 10 are provided to send dashes or short impulses by manipulation in the usual manner. The key 57 is adapted to be closed

by vertical pressure while the key 58 is actuated by horizontal pressure, these keys being provided so that operators accustomed to either motion can manipulate the present device with facility. The keys 57 and 58 are pivoted upon pins 59 and 60, respectively, the circuits being closed by engagement of contact screws 61 and 62 on said keys with stationary contacts 63 and 64, respectively. Proper spacing of the contacts or points may be maintained by suitable adjustment of set screws 65. The circuits are normally maintained open by adjustable compression springs 66. The keys 57 and 58 and automatic switch bar 39 are adapted to be connected in the usual manner in the telegraph circuit.

Operation.

The keys 13 to 17, inclusive, are severally adapted to control mechanism for sending 2 to 6 short impulses. These keys being identical, the operation of all of them will be understood from a description of the operation of one. The operation of the key 15 by which four dots are transmitted, is as follows: When the key 15 is depressed from full line to dotted line position shown in Figure 4, the bar 20 is tilted so as to raise the bar 30 together with the pawl 28, thus releasing the ratchet 27 and shaft 25. The motor 46 immediately turns the shaft 25 in the direction indicated by arrows in Figs. 4 and 5. Simultaneously with tilting of the bar 20, the arm 33 (which is normally in a position to hold the rack 34 out of mesh with the pinion 26) will be moved substantially longitudinally to cause the rack 34 to engage the pinion 26. As the pinion 26 rotates, the rack 34 is carried upward while the dog 24 (being in dotted line position) supports the free end of the bar 20 to hold the pawl 28 out of mesh with the ratchet 27. The rack 34 in its upward movement now strikes the lever 22 and raises said lever to horizontal position, allowing the bar 20 to move back upon the shoulder 21 and simultaneously permitting the pawl 28 to engage the ratchet 27. Rotation of the shaft 25 is thus stopped and the lever 20, being no longer supported upon the dog 24, the rack 34 is withdrawn from engagement with the pinion 26 by the action of the spring 31 and gravity. The rack 33 finally falls upon its support 25 to starting position.

The number of impulses transmitted each time a key is depressed is dependent upon the arc through which the shaft 25 carrying the cam wheel 38 is allowed to rotate. When the key 15 is operated, the cam wheel 38 rotates through an angle sufficient to bring four camming surfaces to bear upon the bar 39. As each camming surface tilts the bar 39, the circuit between the plunger 42 and screw 44 is closed to send a short impulse.

It will now be evident that the number of impulses transmitted when any one of the keys 13 to 17 are manipulated is dependent upon the height of the support 35 for the particular rack arm 33. The key 13, which when actuated, causes two dots to be sent, is thus arranged with the support 35 elevated by the screw 37 so that the cam wheel 38 is only allowed to turn a distance of two notches on its periphery before the rack 34 strikes the lever 22 to stop rotation of the shaft 25 carrying the wheel 38. The height of the several supports 35 beneath the keys 14, 16 and 17 is so regulated by the screws 37 that three impulses will be sent when the key 14 is depressed, while the keys 16 and 17 are severally adapted to control the sending of five and six impulses, respectively.

The keys 57 and 58 are adapted to be struck by the thumb of the operator in the usual manner to send either a single short impulse or the desired number of long impulses or dashes. Any required series of dots may be sent by manipulating a single one of the keys 13 to 17, inclusive.

An important feature of my device is the formation and arrangement of the automatic circuit closer consisting of the switch bar 39 provided with the resilient plunger 42. The spring 43 allows the plunger 42 to remain in firm contact with the stationary contact 44 during the sending of each impulse. The spring 43 causes the plunger 42 to strike the stationary contact with a touch that closely resembles that obtained by proper manual operation of a key. Unusual distinctness is thus obtained so that even when messages are sent with great rapidity they can be received with facility.

Obviously, any desired or suitable type of motor may be substituted for the motor 46 without departing from the spirit of my invention.

Having described my invention what I claim as new and desire to protect by Letters Patent is:

1. In a telegraph transmitting instrument, a normally stationary shaft, means for intermittently rotating said shaft, a switch bar adapted to be vibrated, means operatively connecting said shaft with said bar, a series of keys, means severally connecting said keys with said shaft whereby said shaft is allowed to rotate through predetermined different angles when the several keys are manipulated and means under control of the several keys for positively stopping rotation of said shaft upon the completion of predetermined combinations of vibrations of said bar.

2. In a telegraph transmitting instrument, a single cam wheel, means for intermittently rotating said wheel, a switch bar adapted to be vibrated by rotation of said wheel, a series of keys, and means severally connecting

said keys with said wheel whereby said wheel is allowed to rotate different angular distances when the several keys are manipulated.

3. In a telegraph transmitting instrument, a shaft, means for intermittently rotating said shaft, a switch bar adapted to be vibrated, means operatively connecting said shaft with said bar, a series of keys, a ratchet wheel on said shaft, a pawl adapted to be actuated by said keys to engage and disengage said wheel, and means severally connecting said keys with said shaft and pawl whereby said shaft is allowed to rotate different angular distances when the several keys are manipulated.

4. In a telegraph transmitting instrument, a shaft, a series of pinions fast on said shaft, a switch adapted to be actuated by said shaft, a series of keys, racks arranged to severally connect said keys with said pinions, means for turning said shaft when any of said keys are manipulated, and means operable by said racks to stop rotation of said shaft after the same has turned a predetermined different angle upon the manipulation of the several keys.

5. In a telegraph transmitting instrument, a shaft, a series of pinions fast on said shaft, means for rotating said shaft, a switch adapted to be actuated by said shaft, a series of keys, racks arranged to severally connect said keys with said pinions, a ratchet on said shaft, a pawl arranged to normally engage said ratchet, means for disengaging said pawl to permit rotation of said shaft when any of said keys are manipulated, and means operable by said racks to cause said pawl to stop rotation of said shaft after the same has turned a pre-determined different angle for each of said keys.

6. In a telegraph transmitting instrument, a shaft, a series of pinions fast on said shaft, means for rotating said shaft, a ratchet and pawl arranged to normally prevent rotation of said shaft, a switch adapted to be actuated by said shaft, a series of keys, racks arranged to severally connect said keys with said pinions, dogs adapted to hold said pawl out of engagement with said ratchet and to permit rotation of said shaft when any of said keys are manipulated, and means connected to said dogs and operable by said racks to stop rotation of said shaft after the same has turned a predetermined different angle for each of said keys.

7. In a telegraph instrument, a normally stationary shaft, a series of manually operable keys, means for rotating said shaft when any of said keys are manipulated, a switch bar adapted to be vibrated, means operatively connecting said shaft with said bar, pinions on said shaft, racks severally connecting said keys with said pinions, and dogs adapted to be actuated by said racks to

stop rotation of said shaft when the same has been rotated predetermined different angles for the several keys.

8. In a telegraph instrument, a normally stationary shaft, a series of manually operable keys, means for rotating said shaft when any of said keys are manipulated, a switch bar adapted to be vibrated, means operatively connecting said shaft with said bar, pinions on said shaft, racks severally connecting said keys with said pinions, a ratchet and pawl arranged to normally prevent rotation of said shaft, and dogs adapted to be actuated by said racks to cause said pawl to stop rotation of said shaft when said shaft has been rotated through a predetermined different angle for each of said keys.

9. In a transmitting instrument, a frame, a manually operable key pivotally supported in said frame, a horizontal shaft journaled in said frame, means tending to rotate said shaft, a pinion and a ratchet wheel fast on said shaft, a switch bar, means for vibrating said bar operatively connected to said shaft, a pawl normally disposed to prevent rotation of said shaft by engagement with said ratchet wheel, a dog arranged to maintain said pawl out of engagement with said ratchet when said key is manipulated, a lever on said dog, a rack pivotally connected to said key and adapted to be moved into engagement with said pinion when said key is manipulated, said rack being positioned to strike said lever under the action of said pinion and thereby allow said pawl to stop rotation of said shaft after said key has been manipulated.

10. In a telegraph instrument, a normally stationary shaft, a series of keys, means for rotating said shaft through predetermined different angles when the several keys are manipulated, a switch operatively connected to said shaft, stationary and resilient contact elements arranged on said switch to be 40 pressed one upon the other when said shaft is rotated and means under control of the several keys for positively stopping rotation of said shaft upon the turning thereof through a predetermined angular distance 45 when each key is manipulated.

11. In a telegraph instrument, the combination with a series of keys and a single cam wheel, of means for rotating said wheel through predetermined different angles when the several keys are manipulated, a series 50 of identical camming surfaces at regular intervals on said wheel, a switch adapted to be actuated by said camming surfaces and stationary and resilient contact elements arranged on said switch to be pressed one upon the other when said wheel is rotated.

12. In a telegraph transmitting instrument, a mechanically operated switch comprising, a pivoted bar, a plunger projecting transversely from said bar, resilient means for normally maintaining said plunger in extended position, a stationary contact element disposed opposite said plunger, and means for vibrating said bar to cause the projecting end of said plunger to impinge against said contact element.

In testimony whereof, I have hereunto signed my name to this specification.

WILLIAM D. COOPER.
